UNITED STATES PATENT OFFICE.

LOUIS GOLDSCHMIDT, OF MELROSE HIGHLANDS, MASSACHUSETTS.

COASTING DEVICE.

Application filed March 20, 1925. Serial No. 16,980.

To all whom it may concern:

Be it known that I, LOUIS GOLDSCHMIDT, a citizen of the United States, and a resident of Melrose Highlands, in the county of Middlesex and State of Massachusetts, have invented an Improvement in Coasting Devices, of which the following description, in connection with the accompanying drawings, is a specification, like characters on the drawings representing like parts.

My invention relates to vehicular or like devices for coasting on snow or ice and adapted for use alike by adults or children for amusement, competitive sports, or conveyance purposes.

In the drawings illustrating by way of example certain embodiments of my invention:

Fig. 1 is a side elevation of a device embodying one form of my invention;

Fig. 2 is a plan view thereof;

Fig. 3 is a vertical section, on a larger scale, taken along the line 3, 3 of Fig. 1;

Fig. 4 is a cross section, upon a still larger scale, taken upon the line 4-4 of Fig. 1, looking down;

Fig. 5 is a view similar to Fig. 1, showing a modified construction also embodying my invention;

Fig. 6 is a plan of the device of Fig. 5.

The coasting, sledding or like device or apparatus of my invention may be made in various sizes ranging from those suitable for small children up to those for use by adults.

Referring more particularly to the drawings, and first to Figs. 1 to 4, the device there shown comprises a plurality of shoes, runners, or runner elements including a front runner 1 and a rear runner 2. Said

front and rear runners may be identical in shape and size to facilitate manufacture thereof in quantity, but preferably the rear runner is somewhat longer than the one in front, affording a larger supporting area.

Said runners as illustrated have a skee-like formation including up-turned portions or toes 3, 3 at the front ends and desirably one or more longitudinal ribs 4, 4 upon their under surface, of general V-shape in cross section and serving to counteract side-slip of the device.

Said front and rear runners 1, 2, Figs. 1 and 2, are arranged in tandem, being connected by a suitable frame mounted thereon. Any strong and preferably light material may be employed in forming the

frame, such as certain woods or metals. Preferably, however, and as herein shown the frame is composed of a small plurality of tubular metallic members or metal tubes, including a front upright or post 5 and a rear upright or post 6. Said posts, which are desirably inclined slightly toward each other substantially in the manner illustrated, are interconnected by a suitable longitudinal tie or strut element, member, or members. Herein such longitudinal connecting element includes a pair of opposed, arcuate metal tubes 7 and 8 disposed one above the other in concavo-convex or X-like relation, and connected at substantially the central portions of their curves, as by the bolt or rivet 9. The construction and arrangement of the tubular frame members as shown and described affords a frame of great strength and rigidity, and which is symmetrical and evenly balanced. Such construction enables the device easily to be carried as by grasping it adjacent the point of connection 9 of the longitudinal tie members. When there supported the weight of the device is substantially equally distributed to the front and to the rear. It will be noted that the front and rear posts 5 and 6 at their lower portions are substantially continuations of the line of curvature of the lower arcuate member 8 or tangential thereto whereby the frame is given an arch-like form of maximum strength consistent with lightness.

Mounted on the frame is a suitable seat 90 desirably resiliently supported, herein by means of the seat post 11 which extends downwardly within the upper end of the tubular rear post 6 and rests upon a coil spring 12 having a suitable bearing support 95 within the tube, herein provided by a cross-pin 13. Movement of the seat is limited in any suitable manner, as by means of the longitudinal slot 14 in the rear post in which rides a pin 15 projecting radially 100 from the seat post 11. Said seat is thus connected to the rear post but permitted to yield substantially vertically relatively thereto and at the same time is prevented from objectionable transverse or turning movement. 105

The runners or runner elements are attached at the lower extremities of the front and rear posts respectively in any suitable manner but preferably in such way as to permit them to have a vertical rocking or pivoted movement, whereby the coasting device readily accommodates itself to surface 110

irregularities of the snow or ice. Accordingly there is secured upon the upper surface of each of the runners 1, 2 a block or lug 16, seen in detail in Fig. 3, and adapted for pivotal attachment to the frame. Desirably the rear runner 2 is permitted only a vertical rocking movement relative to the frame. The rear post 6 is accordingly formed with a vertical, longitudinal slot at its lower extremity, within which the block 16 of the rear runner is received. A pin or bearing 17 is passed transversely through said block and the portions or ears on said post at opposite sides of the slot. Said block 16 is of a width substantially equal to that of the slot in the rear post so as to have a close, working fit therein when pivoting about the pin 17, while said block and ears have sufficient longitudinal extent to prevent relative movement between them in a transverse or horizontal plane. The described construction is strong, simple and efficient for the purpose intended.

The front runner 1 is preferably mounted for substantially universal pivoted or rocking movement, being movable not only vertically but also transversely, for steering purposes. As best seen in Fig. 3, the block 16 of said front runner is pivotally secured, by means of a pin 18 and in a manner similar to that of the rear runner, between ears 19 at the lower end of a member 20 herein shown as a sleeve upon the upper end of which the front post 5 rests. Said member 20 is fast upon or formed integrally with the lower end of a steering post 21 being herein secured thereto, as by means of pins 22, 22; see Fig. 3. Said steering post extends upwardly through the tubular front post 5 and is adapted to turn relatively thereto about its longitudinal axis. At its upper end said steering post is provided with suitable manual control means, herein including a steering or handle bar 23 having the hand grips 24, 25.

Desirably the steering movement of the front runner is limited to approximately 180 degrees, 90 degrees to either side of its normal, straight front position. For this purpose any suitable means may be employed and herein I have shown a stop 26 which may be a pin projecting radially from the steering post and adapted to bring up against the shoulders 27, 28 on the front post 5 at one or the opposite limits of the steering swing desired for the front runner. Said pin 26 also serves to hold the steering post and front tubular post in assembled position when the device or vehicle is being carried.

To assist the operator in mounting the coaster a mounting step 29, Figs. 1 and 2, may be provided at the rear portion of the frame, while at a convenient point at the front of the latter a suitable foot-rest 30

may be provided, to support the feet of the operator, when desired.

In Figs. 5 and 6 I have shown a coasting device also embodying my invention and which in all respects not otherwise mentioned may be the same as that of Figs. 1 to 4. As illustrated in Figs. 5 and 6 the device or apparatus is self-supporting, that is, it will stand upright without other support. It may conveniently be termed a tri-runner device, as compared with the bi-runner device of Figs. 1 to 4.

Referring still to Figs. 5 and 6, near the lower end of the rear post 6', desirably below the point at which the lower longitudinal tie member 8 joins it, there is secured a cross bar 31. Upon the opposite ends of said cross bar are mounted runners 32, 33 which in detail may be the same as the rear runner 2 of Figs. 1 to 4. Said cross bar 31 desirably terminates at its opposite sides in portions 34, 35 extending substantially at right angles to the plane of the runners, so as to permit free vertical rocking movement of the latter. Said cross bar may also serve as a mounting step, in which case the step 29 may be omitted. Obviously, if desired, and within the scope of my invention, the front runner element may also be double, or other arrangement and number of runners employed.

From the foregoing it will be understood that the vehicle, coaster or winter-sports device embodying my invention comprises a plurality of runner elements connected by a suitable strong, light frame desirably supporting a seat for the operator or rider. Preferably the runners are individually rockable vertically relative to the frame, while the front runner or runners are in addition capable of pivoted movement transversely of the frame, for steering purposes, although in some instances, as in coasting upon prepared slides such provision for steering need not be employed.

My invention is not limited to the specific embodiments thereof shown and described herein.

Claims:

1. A frame for a snow or ice runner-mounted coasting device, comprising in combination front and rear upwardly converging uprights and upper and lower arcuate, oppositely disposed, longitudinal tie members intermediate said uprights, said members being in contact at substantially their midlength points and there interconnected, the lower member being connected at its opposite ends to said uprights adjacent the lower ends thereof so that the latter form substantially a continuation of the line of curvature of said lower tie member, and said upper tie member being connected at its opposite ends to said uprights near their upper extremities and at approximately right

angles thereto so as to oppose with maximum efficiency any tendency of said uprights there to give toward each other, said uprights and tie members together providing a frame symmetrical at front and rear of the point of contact of said tie members, at which point the device may readily be grasped and supported by the operator for carrying purposes with the weight substantially evenly balanced to front and rear.

2. A frame for a snow and ice runner-mounted coasting device, comprising front and rear uprights, said rear upright having

means at its upper end for supporting a seat and said front upright being formed as a bearing sleeve for a steering post, and a pair of longitudinal arcuate tie members intermediate said uprights and oppositely disposed in the same vertical plane, so as to contact at substantially their midlength points thus providing a grasping portion to permit the frame to be readily carried in a balanced condition.

In testimony whereof, I have signed my name to this specification.

LOUIS GOLDSCHMIDT.
